UNITED STATES PATENT OFFICE

ARTIE F. MCFARLAND AND ARTHUR E. MCFARLAND, OF HOUSTON, TEXAS

INTERNAL COMBUSTION MOTOR

Application filed February 21, 1929. Serial No. 341,774.

This invention relates to new and useful improvements in an internal combustion motor.

One object of the invention is to provide an internal combustion motor having its cylinders arranged in pairs, the cylinders of each pair being aligned, with pairs of pistons in the respective pairs of cylinders, the pistons of each pair being connected together by a 10 piston rod and being connected also to a common crank shaft by means of a single connecting rod.

Another object of the invention is to provide a novel assembly of cylinders and pistons 15 arranged in pairs, the cylinders of each pair being in alignment, with a common crank shaft to which the pistons of each pair are connected by a single connecting rod.

A further feature of the invention is to 20 provide an internal combustion motor of the character described equipped with means for compressing air without interfering with the operation of the motor.

With the above and other objects in view 25 this invention has particular relation to certain novel features of construction, operation, and arrangement of parts, an example of which is given in this specification and illustrated in the accompanying drawings, 30 wherein:

Figure 1 shows a fragmentary longitudinal vertical sectional view of one type of the motor.

Figure 2 shows a transverse vertical sec- 35 tional view, taken on the line 2—2 of Figure 1.

Figure 3 shows a fragmentary longitudi- 40 nal sectional view of another type of the motor.

Figure 4 shows a transverse vertical sec- 45 tional view thereof, taken on the line 4—4 of Figure 3, and Figure 5 shows a fragmentary vertical sectional view thereof.

Referring now more particularly to the 50 drawings, wherein like numerals of reference designate similar parts in each of the figures the numeral 1 designates the crank case of an internal combustion motor having a conventional crank shaft 2 rotatable in suitable bearings 3, therein. Mounted on this crank case is the cylinder block 4 having the

cylinders 5, 5' alternately arranged therein. On this block there is a head plate 6, on which there is mounted another cylinder block 7 having the cylinders 8, 8' alternately arranged therein. The cylinders 5 are aligned with the corresponding cylinders 8' and the cylinders 5' are aligned with the corresponding cylinders 8 and the outer ends of the cylinders 8, 8' are closed by the head 9. The cylinders are thus arranged in pairs and working in the respective pairs of cylinders 5, 8' are the corresponding pairs of pistons 10, 11' and working in the cylinders 5', 8, are the pistons 10', 11. The pistons of the respective pairs are connected by the respective rods 12 which work through the corresponding stuffing boxes 13 in the head plate 6. The pistons 10, 10' are connected to the respective wrists of the crank shaft by the connecting rods 14. The cylinders 5, 8 are connected by the conduits 15, 15 and the cylinders 5', 8' are connected by the conduits 16, 16. Each cylinder has a firing chamber 17, formed in the head plate 6 and communicating with the inner end of the corresponding cylinder and there is the usual spark plug anchored to said head plate and arranged to fire the charge in the chamber 17. There is an intake manifold 19 through which the explosive mixture is admitted to the respective explosion chambers of the cylinders, the intake of the charges being controlled in the well known manner by the intake valve 20 which is opened by the usual cam shaft 21 and closed by the usual spring 22.

When a charge is admitted into one of two connected cylinders part of it will pass into the other of said connected cylinders forming, in effect, two charges which will be simultaneously compressed, and simultaneously fired, and the spent products will be simultaneously exhausted. An increase of power will thus be obtained without lengthening the motor and a more compact power unit will thus be produced having eight cylinders, without increasing the length, over the ordinary four cylinder motor.

The construction hereinabove described may also be used as an efficient air compressor by connecting a delivery line 23 into the

55

100

respective cylinders 8, 8', through the branches 24, 24'. These branches should be equipped with the check valves 25. When used, as an air compressor the respective cylinders 8, 8' should also have the inlet pipes 26, 26' equipped with the corresponding check valves 27, 27'. Whether used as an air compressor, or as a motor only, the respective pairs 8, 8' of cylinders should be connected 5 by the by-pass pipes 28, 28, as shown which are equipped with suitable valves 29, 29 by means of which they may be opened and closed. When used as a motor only the pipes 23, 24, 24' and 26 will be removed and the 10 valves 29 opened to permit the air to pass freely between the cylinders connected by the pipes 28, 28. When employed as an air compressor the valves 29 will be closed.

In the form shown in Figures 3 and 4 the 20 numeral 30 designates the crank case on which the cylinder block 31 is mounted. This block is shown as having six cylinders 32 to 37 inclusive and mounted on the outer end of the block there is the head plate 38. 25 Mounted on this head plate 38 there is a cylinder block 39 having the cylinders 40 to 45 inclusive aligned with the corresponding cylinders 32 to 37 thus forming pairs of cylinders, and the cylinders of each pair being 30 in alignment. The outer ends of the cylinders of the block 39 are closed by the head 46 which is suitably secured to said block 39. In the pairs of aligned cylinders are the corresponding pairs of pistons 47 to 52 inclusive and 53 to 58 inclusive. The pistons of the respective pairs are connected by the rods 59 to 64 inclusive and said pairs of pistons are connected, by the respective connecting rods 65 to 70 inclusive, to the corresponding wrists of the crank shaft 71 which is mounted in the crank shaft bearings 72 in the crank case 30.

In this form of the motor there is an intake manifold 73 through which the explosive mixture is delivered into the firing chambers as 74, 74' which communicate with the corresponding explosion chambers of the cylinders of the respective pairs of cylinders. There are the spark plugs, as 75, 75', anchored 45 to the firing chamber walls and adapted to fire the charges in said chambers.

The admission of the charges to the respective pairs of cylinders are controlled by the usual intake valves, as 76, 77, normally 55 held closed by the respective springs 78, 79. The valve 78 may be actuated from the cam shaft 80, in the usual way. There are the two rocker arms 81, 82 mounted in the respective blocks 31, 39 and between the outer 60 ends of these arms there is a push rod 83. There is a push rod 84 through which the cam shaft 80 acts to actuate the rocker arm 81. The cam shaft 80 thus operates to open the valves 76, 77 to admit the charges to the 65 cylinder of each pair in proper sequence, such

result being accomplished by the cam 85, on said shaft 80.

The respective pairs of cylinders are equipped, also, with suitable exhaust valves 76', 77', which are arranged to be opened 70 in proper sequence, from the cam shaft 80 through valve actuating mechanism shown in Figure 5 and similar to that described and shown in Figure 4.

In the form of motor shown in Figure 4 75 the explosions are timed to occur in the respective cylinders successively in the sequence indicated by the letters A to L inclusive.

A twelve cylinder motor may thus be produced of a practical length and width and equipped with a single crank shaft and with only six connecting rods.

The drawings and description are for the purpose of illustrating preferred forms of the 85 invention, by way of example, while the broad scope of the invention is defined by the appended claims.

What we claim is:

1. An internal combustion motor including 90 cylinders arranged in pairs, a common head plate separating the cylinders of each pair, said head plate having conduits connecting the combustion chambers of cylinders on opposite sides thereof, pairs of pistons in the respective pairs of cylinders, rods connecting the pistons of each pair of pistons, a crank shaft, and connecting rods connecting the respective pairs of pistons to the corresponding wrists of the crank shaft.

2. An internal combustion motor including 95 two series of cylinders, the cylinders of one series being aligned with the cylinders of the other series, forming pairs of aligned cylinders, a head plate separating the respective 100 series of cylinders, pairs of pistons in the respective pairs of cylinders, rods connecting the piston of each pair, said head plate having bearings through which the rods work, a crank shaft, connecting rods connecting the respective pairs of cylinders with the wrists of said crank shaft, there being conduits through said head plate through which the combustion chambers of the cylinders of one 105 series are connected with the combustion chambers of the cylinders of the other series.

3. An internal combustion motor including 110 two series of cylinders, the cylinders of one series being aligned with the cylinders of the other series, forming pairs of aligned cylinders, a partition separating the respective 115 series of cylinders, pairs of pistons in the respective pairs of cylinders, rods connecting the pistons of each pair, said partition having bearings through which the said rods work, a crank shaft, connecting rods connecting the respective pairs of cylinders with the wrists of said crank shaft, there being conduits through said partition through which the combustion chambers of the respective cyl- 120 125 130

inders of a pair are connected with the combustion chambers of the cylinders of an adjacent pair.

4. An internal combustion motor including
5 a series of cylinders arranged in pairs, pairs
of pistons reciprocable in the respective pairs
of cylinders, each cylinder having a combustion
10 chamber on one side of its piston and the
cylinders of one series having compression
chambers on the other side of the pistons
thereof, means connecting the pistons of each
15 pair, a crank shaft, connecting rods connecting
the respective pairs of pistons to said
crank shaft, valve controlled bypass conduits
connecting the said compression chambers, in
pairs and means through which explosive
20 charges may be admitted into said respective
combustion chambers by suction only.

5. An internal combustion motor including
20 two series of cylinders, the cylinders of one
series being aligned with the cylinders of
the other series, forming pairs of aligned cyl-
inders, each cylinder having a combustion
25 chamber on one side of its piston and the cyl-
inders of one series having compression cham-
bers on the other side of the pistons thereof, a
head plate separating the respective series of
30 cylinders, pairs of pistons in the respective
pairs of cylinders, rods connecting the pis-
tons of each pair, said head plate having bear-
ings through which the said rods work, a
crank shaft, connecting rods connecting the
35 respective pairs of pistons with the wrists of
said crank shaft, a valve controlled delivery
line connected into the said compression
chambers, and valve controlled air inlets for
said last named cylinders.

6. An internal combustion motor including
40 cylinders arranged in pairs, a common parti-
tion separating the cylinders of each pair,
there being conduits connecting the combus-
tion chambers of the cylinders on opposite
45 sides of the partition, pairs of pistons in the
respective pairs of cylinders, rods connecting
the pistons of each pair of pistons, a crank
shaft and connecting rods connecting the re-
spective pairs of pistons to the correspond-
ing wrists of the crank shaft.

7. An internal combustion motor includ-
50 ing two series of cylinders, the cylinders of
one series being aligned with the cylinders
of the other series, forming pairs of aligned
cylinders, a partition separating the respec-
55 tive series of cylinders, pairs of pistons in
the respective pairs of cylinders, each cyl-
inder having a combustion chamber on one side
of its piston and the cylinders of one series
having compression chambers on the other
60 side of the pistons thereof, rods connecting
the pistons of each pair, said partition having
bearings through which the said rods work,
a crank shaft, connecting rods connecting the
65 respective bearings of the pistons with the
wrists of said crank shaft, a valve controlled
delivery line connected into the said com-

pression chambers, valve controlled air in-
lets for said compression chambers, and valve
controlled bypass conduits connecting the
said compression chambers in pairs.

In testimony whereof we have signed our 70
names to this specification.
